BEVERAGE BREWING DEVICE

Fred C. Schwanek, Chicago, Ill.

Application June 1, 1954, Serial No. 30,745

Term of patent 14 years

(Cl. D44—26)

Fig. 3.

To all whom it may concern:

Be it known that I, Fred C. Schwanke, a citizen of the United States, residing in the city of Chicago, county of Cook, and State of Illinois, have invented a new, original, and ornamental Design for a Beverage Brewing Device, of which the following is a specification, reference being had to the accompanying drawings forming a part thereof.

Fig. 1 is a side elevational view of a beverage brewing device showing my new design, the opposite side thereof being substantially the same except for the handle;

Fig. 2 is a top plan view thereof; and

Fig. 3 is a front elevational view thereof with the central top portion raised.

The back elevational view is substantially like the front elevational view, except for the spout.

I claim:

The ornamental design for a beverage brewing device, as shown and described.
